INVENTOR

Edwin E. Slick
By my attorney
Garnett Parnell
his atty.

UNITED STATES PATENT OFFICE.

EDWIN E. SLICK, OF PITTSBURGH, PENNSYLVANIA.

MOUTHPIECE FOR TRANSMITTERS.

Application filed May 28, 1927. Serial No. 194,921.

The present invention has for one of its objects, the provision of an improved mouth piece particularly adapted for use with telephones and possessing greater durability and 5 more pleasing appearance than mouth pieces as now constructed and capable of being cleansed as desired for sanitation purposes.

At the present time, it is customary to construct mouth pieces of the general nature 10 herein contemplated, of molded material such, for example, as gutta percha or the like. Such mouth pieces provide an abrupt change of section adjacent the threaded end, and not infrequently they are broken during ordinary 15 handling of the 'phone. Also, due to the ease with which the threads on mouth pieces so formed are broken, mutilated or stripped, they are not adapted to withstand rough usage, nor are they capable of frequent removal and cleansing as may be desirable from 20 a standpoint of sanitation.

In accordance with the present invention, I provide a mouth piece of glass having a reinforced terminal portion, the reenforcement 25 preferably being such that it constitutes a threaded male member for engagement with the transmitter.

In the accompanying drawings, I have shown for purposes of illustration only, one 30 preferred embodiment of the present invention, it being understood that the drawings do not define the limits of my invention inasmuch as changes may be made in the material of which the transmitter is constructed as well as 35 in the contour and arrangement thereof without departing from the spirit of the present invention or the scope of my broader claims.

In the drawings,

Figure 1 is a vertical sectional view through 40 one form of mouth piece embodying the present invention;

Figure 2 is a bottom plan view of a mouth piece constructed in accordance with the present invention; and,

Figure 3 is a side elevation of a completed mouth piece.

In carrying out the present invention, there may be provided a mouth piece comprising a main body portion 2 of a moldable material 50 such, for example, as glass. Glass is chosen by reason of the fact that it may be subjected to repeated cleansing operations and for the further reason that it presents an attractive appearance.

During the molding of the mouth piece, there is incorporated therewith a reenforcing

means preferably in the form of a sleeve 3 continuously threaded throughout its length. This sleeve serves as a reenforcement for the mouth piece adjacent the end which engages 60 the transmitter, and which end is usually weakened to a considerable degree by reason of the abrupt change of section necessary to accommodate the threads by means of which engagement is made with the transmitter. By 65 reason of a sleeve threaded throughout its length, the threads on the upper portion thereof serve to embed the sleeve in the glass body and prevent displacement or relative movement between the parts. 70

Furthermore, the provision of a threaded sleeve provides a construction which is symmetrical with respect to its opposite end portions, thereby preventing possibility of error in positioning the sleeve within the mold. 75

If desired, the mold may be so shaped as to provide a projecting annular portion 4 of glass adapted to lie within the sleeve and completely cover the internal surface thereof.

The sleeve being of metal, affords adequate 80 reenforcement for the mouth piece body, and at the same time provides a substantially indestructible thread enabling the mouth piece to be repeatedly removed from and applied to a transmitter without destruction of such 85 threads. This constitutes one of the advantages of the present invention.

A further advantage of the invention arises from the provision of a mouth piece having reenforcing means provided therefor 90 adjacent the abrupt change of section in the mouth piece.

Still further advantages arise from the provision of a mouth piece having incorporated therein a reenforcing sleeve preferably 95 threaded throughout its entire length to provide end portions of similar characteristics.

I claim:

1. As an article of manufacture, a molded mouth piece for transmitters having an 100 abrupt change of section in one portion thereof and re-enforcing means embedded in the mouth piece beyond the change of section and removed from the inner surface of the mouth piece, whereby the interior of the 105 mouth piece presents a continuous surface of molded material from end to end.

2. As an article of manufacture, a molded mouth piece for transmitters having an 110 abrupt change of section, and re-enforcing means mounted on the exterior of the mouth piece adjacent to one end thereof, the molded

material forming a lining for the reinforcing means throughout its entire length.

3. A mouth piece for transmitters comprising a body portion of frangible material having a portion of abrupt change of shape at one end and re-enforcing means disposed exteriorly of the frangible material which forms a lining therefor throughout its entire length.
- 10 4. A mouth piece for transmitters com-

prising a body portion of frangible material having a portion of abrupt change of shape at one end and re-enforcing means disposed exteriorly of the frangible material which forms a lining therefor throughout its entire 15 length, and having means for engaging a supporting member.

In testimony whereof I have hereunto set my hand.

EDWIN E. SLICK.
